US00D734155S

(12) **United States Design Patent**
Moore et al.

(10) **Patent No.:** US D734,155 S
(45) **Date of Patent:** ** Jul. 14, 2015

(54) **SCREW-TOP CONTAINER**

- (71) Applicant: **Silgan Containers LLC**, Woodland Hills, CA (US)
- (72) Inventors: **Seth Moore**, Oconomowoc, WI (US); **Matt R. Brown**, Gretna, NE (US); **Gerald J. Baker**, Wauwatosa, WI (US); **William Kapolas**, Palatine, IL (US)
- (73) Assignee: **Silgan Containers LLC**, Woodland Hills, CA (US)
- (**) Term: **14 Years**
- (21) Appl. No.: **29/483,559**
- (22) Filed: **Feb. 28, 2014**

Related U.S. Application Data

- (63) Continuation of application No. 29/464,345, filed on Aug. 15, 2013, now Pat. No. Des. 703,057, which is a continuation of application No. 29/438,094, filed on Nov. 26, 2012, now Pat. No. Des. 690,599, which is a continuation of application No. 29/398,996, filed on Aug. 8, 2011, now Pat. No. Des. 676,764, which is a continuation of application No. 11/811,362, filed on Jun. 8, 2007, now abandoned.

(57) **CLAIM**

We claim the ornamental design for a screw-top container, as shown and described.

DESCRIPTION

FIG. 1 is a perspective view of an embodiment of the claimed design;

FIG. 2 is a front view of the claimed design of FIG. 1;

FIG. 3 is a rear view of the claimed design of FIG. 1;

FIG. 4 is a left side view of the claimed design of FIG. 1;

FIG. 5 is a right side view of the claimed design of FIG. 1; and,

FIG. 6 is a top view of the claimed design of FIG. 1.

The broken lines shown are included for the purpose of illustrating portions of the screw-top container that form no part of the claim.

1 Claim, 6 Drawing Sheets
